UNITED STATES PATENT OFFICE.

GEORGE W. MCGILL, OF RIVERDALE-ON-HUDSON, NEW YORK.

METALLIC FASTENER.

No. 893,852.

Specification of Letters Patent.

Patented July 14, 1908.

Application filed April 12, 1906. Serial No. 311,224.

To all whom it may concern:

Be it known that I, GEORGE W. MCGILL, a citizen of the United States, and a resident of Riverdale-on-Hudson, in the county of New York and State of New York, have invented certain new and useful Improvements in Metallic Fasteners, of which the following is a specification.

My invention relates to metallic fasteners having for their object the binding together of sheets of paper, and other like material, and for light binding of various kinds.

The fastener I desire to patent is made from a blank of sheet metal divided by folds into three sections or members, one section being provided with a tang, another section provided with a slot through which such tang is passed in the process of applying the fastener to use as intended, and the third section provided with a curved anvil surface from which the free end of the tang is bent over and clenched upon one surface of the slotted section; two of such sections providing the facing members of the device between which the material being fastened is clamped and pinioned.

The object of my improvement is to provide the fastener with means to prevent the unintentional separation of its clamping parts when the device is applied as intended, and to cause these parts to rivet and lock themselves together through the process of such application, and through such process to securely bind and lock between them the material to which the device is applied.

In the accompanying drawing forming part of this specification and in which similar letters and numerals of reference indicate corresponding parts, Figure 1, represents a plan view of the device before the folding of its sections or members into position. Fig. 2, is a similar view showing its anvil or clenching member folded over its slotted or bur member and secured in position thereon. Fig. 3, is a longitudinal sectional view of Fig. 2. Fig. 4, is a view in perspective of the completed fastener in position for application to the use intended, and Fig. 5, is a longitudinal section of the fastener applied as intended in binding together sheets of paper or other material. Figs. 6 to 15, inclusive, show modifications in the construction of the fastener hereinafter fully described.

In the Figs. 1 to 10, inclusive, A, and B, represent the facing or clamping members of the device, and C, its anvil, or tang-clenching

and covering member which in the completed fastener is seated permanently parallel with the outer surface of the slotted member in order to have its anvil face the slot of that member. The dotted lines 1, 2, indicate the location of the transverse bends or folds connecting the three sections or members in the completed device. 3, is a tang, or tooth, punched outward from, and at its root integral with the member A. 4 is a slot or aperture in the member B, for the reception of the projecting end of the tang 3, after its passage through the material being bound between the clamping or facing members. 5, is a lip projecting from the edge of the slot 4 nearest the fold 1, of the members A, B, and over which the tang 3 is bent. 6, is a tubular riveting pillar struck up from the plane of the member B, and integral therewith. 7, is a depression or reentrant cavity struck in the member C, relatively deep and broad at one end and shallow and narrow, or pointed, at its other end, and forming a depressed anvil-surface therein upon which the free end of the tang 3, is deflected over and clenched upon the member B, and beneath which it is housed and concealed, and 8, is an aperture, or eye, in the free end of such member C for the reception of the free end of the pillar 6. The member C, is folded over upon the member B, at the line 2, bringing its eye, 8, over the tubular riveting pillar 6, of the latter member and the concave surface of its anvil 7, over the slot 4, in said member, B. The members B, and C, so placed, are riveted together by upsetting the top of the tubular pillar 6, upon the flange of the eye in the end of the member C, as shown in Figs. 2, 3, 4, 5. The clamping or facing members A, and B, are now folded toward each other at the line 1, as shown in Fig. 4, completing the device and putting it in condition to be put in use as intended, which is accomplished by placing between such facing members the material, marked 9 in the drawing, to be bound, and pressing together the free ends of such members, which operation causes the free end of the tang 3, to pierce and pass through the material and through the slot 4, in the member B, and to enter the anvil 7, in the member C, and engage therein with its concave surface which deflects it over the lip, 5, of the slot 4, and clenches its point down upon that part of the surface of the member B, covered by the anvil, as shown in the sectional Fig. 5, whereby the free end of both clamping mem-

bers are riveted together with the fastened material between them. The depth of the concave curvature of that part of the sunken anvil-face which covers the edge of the slot 4 nearest the fold 2 of the members, should be sufficient to enable the free end of the tang 3, to pass some distance through and beyond the slot 4, before engaging with the anvil-face to secure the proper deflection of the tang down and forward over such lip, and over the anvil-covered surface of such member; the object of the lip being to prevent any play between the deflected or bent over part of the tang and such covered surface, by providing a fulcrum or prop over which it is bent, but the lip may be omitted without materially lessening the efficiency of such clenching. The tubular riveting pillar 6, of such member, and the coacting receiving eye, 8, in the member C, may also be omitted without materially impairing the operation of such clenching, the fold, 2, of the metal connecting such members being substantially sufficient to hold them together in the rigid parallel contact required.

In the drawing Figs. 6, 7, 8, 9 and 10, respectively, correspond in kind and construction with the Figs. 1, 2, 3, 4 and 5, excepting that in the former figures are omitted the lip 5, the tubular pillar 6, and the receiving eye 8, shown in the latter figures.

Figs. 11, 12, 13, 14, and 15, respectively, correspond in kind and construction with Figs. 6, 7, 8, 9 and 10, excepting that in the former figures the intermediate member, B', instead of the end member, C, as in the latter figures, is provided with the clenching anvil, 7'; and the end member, C', in the former figures instead of the intermediate member, B, as in the latter figures, is provided with the tang receiving slot, 4'; and the end member, C', of the former figures is folded inward under the intermediate member, B', instead of upward and over the intermediate member, as in the former and other corresponding figures of the drawing.

To secure accuracy in the coaction of the interlocking parts of the clamping members, the fold connecting them may preferably be but little less in width than the width of the respective members; and to facilitate the ready closing of this fold by the fingers in applying the device its rigidity may be reduced by removing, at such fold, a section of metal transversely crossing it, as shown in Figs. 6-9.

Having thus fully described my invention what I claim as new and desire to secure by Letters Patent is:—

60 1. A metallic fastener of the character described, made from a blank of sheet metal divided by folds into three coacting members, one of which is provided with a tang, another with a slot and a third with an anvil; the slot 65 in one member being adapted to receive the

free end of the tang of the other member, and the anvil of the third member having throughout its length a decreasing depth and curvature of its face to deflect and clench the free end of the tang over upon the outer surface of the member possessing the slot, and to thereby rivet that member with the member possessing the tang, with the material being fastened strung on the tang, and clamped and locked between said riveted members 75 on the fastener being put to the use intended.

2. A metallic fastener presenting two facing clamping members and one anvil or clenching member, one of the members being provided with a penetrating tang adapted to 80 penetrate the material being held between the clamping members, another member provided with a slot to receive the free end of such tang on its exit from such material, and a third member having one of its surfaces recessed in manner to provide it with a sunken anvil surface, the face of such anvil member being seated in permanent bearing with the back of the slotted member, and the slot of the latter being permanently covered by the 85 sunken anvil face of the former, with such anvil face possessing a graded curvature adapting it, when borne against by the tang on the bringing together of the free ends of the clamping members, to deflect the free 90 end of such tang in the direction of the fold of the clamping members and to clench it over upon the anvil covered surface of the slotted member and thereby rivet those members together, with the papers clamped between 95 them strung on the tang.

3. A metallic fastener presenting two facing clamping members and one anvil or clenching member, one of the members being provided with a penetrating tang adapted to 105 penetrate the material being held between the clamping members, another member provided with a slot to receive the free end of such tang on its exit from such material and a third member having struck in one of its 110 surfaces a recessed anvil-face of a depth greater at its one end than at its other, such anviled member being folded over and seated in permanent parallel contact with the slotted member and with the deeper end of 115 its anvil-face bridging the slot of such member.

4. A metallic fastener of the character described consisting of three coacting members integrally connected, one of the members being 120 provided with a penetrating tang, a second member provided with a slot for the reception of such tang, and a third member having a recessed and ridged anvil-face sunk in one of its surfaces and forming a reentrant 125 cavity therein, one end of such cavity having a depth greater than that of its other end with the space intermediate such ends sunken and graded to correspond with the depth of such ends; said anvil member being folded 130

over and seated in permanent parallel contact with the slotted member and with the deeper end of its anvil face, or cavity, bridging the slot of such member and adapted to receive therein and to deflect and force therefrom the pointed end of the tang and to seat it over upon the covered surface of said slotted member and to house it thereon.

5. In a metallic fastener of the character described, a member provided with a depression or reentrant cavity the inner surface of which constitutes a curved anvil face sunk therein deeper at one end than at its other end, and adapted to cover a tang-receiving slot in an adjoining member and to engage with the point of a tang projected through such slot, and by the shape of its face to deflect and bend the point of said tang over the surface of such adjoining member bor-

dering such slot, and to clench and house 20 it therein.

6. A metallic fastener of the character described providing a plurality of coacting members one of which is provided with a slot having one of its edges projected outwardly from the plane of such member and providing a lip adapted to serve as a fulcrum over which a tang of another member is folded in locking together both such members in applying the device to the uses intended. 25

Signed at New York city in the county of New York and State of New York this 11th day of April A. D. 1906.
